(57) **CLAIM**

The ornamental design for a weightlifting equipment rack, as shown and described.

DESCRIPTION

FIG. 1 is top perspective view of a weightlifting equipment rack showing our new design;

FIG. 2 is a front view thereof;

FIG. 3 is a left side view thereof;

FIG. 4 is a rear view thereof;

FIG. 5 is a top plan view thereof; and,

FIG. 6 is a bottom plan view thereof.

The broken lines in the drawings depict environmental subject matter only and form no part of the claimed design.
